A. B. KENDALL.
SELECTOR RELAY.
APPLICATION FILED MAY 20, 1916.

1,253,194.

Patented Jan. 8, 1918.

UNITED STATES PATENT OFFICE.

ALLEN B. KENDALL, OF ELIZABETH, NEW JERSEY, ASSIGNOR TO HALL SWITCH & SIGNAL CO., A CORPORATION OF MAINE.

SELECTOR-RELAY.

1,253,194.

Specification of Letters Patent. Patented Jan. 8, 1918.

Application filed May 20, 1916. Serial No. 88,972.

To all whom it may concern:

Be it known that I, ALLEN B. KENDALL, a citizen of the United States, and a resident of the city of Elizabeth, county of Union, 5 and State of New Jersey, have invented a certain new and useful Selector-Relay, of which the following is a specification.

My present invention relates to a selective relay and is shown in use, controlling a 10 signal system, in my prior application Serial Number 783,506, filed August 7th, 1913, this application being a continuation in part of the above mentioned application.

It will be obvious that such a device as 15 disclosed is susceptible to quite a variety of modifications without departing from the broad spirit of the invention, such as applying the device for the control of grade crossing bell, signals, tower annunciators or the like.

I have already described in my application Serial Number 783,506 the application of my relay to an absolute permissive block 20 signal system, and I will now proceed to describe how my invention may be employed to control, respectively, a crossing bell and a wig wag crossing signal of the normally 25 closed circuit type, at a railroad crossing where trains pass in both directions over the same track.

With a relay of the interlocking type it was fundamentally impossible to use the relay for the normal control of the track signals, annunciators or the like, as well as the 30 crossing signals, and it is the object of the present invention to overcome this difficulty, allowing both armatures to fully complete their stroke, irrespective of the sequence of 35 their operation, as well as rectifying various other defects in prior relays, as can be seen by the following description and claims.

Figure 1. is a diagrammatical view of my selector relay arranged to control a normally energized crossing signal.

Fig. 2. shows the various conditions of the selector contacts when adjusted to control a normally closed signal circuit.

Fig. 3. shows the various conditions of the selector contacts when controlling a bell circuit, and

Fig. 4. is a diagrammatical view of my se-

lector relay as arranged for the control of a crossing bell.

Referring to Fig. 1, two sections of track are represented at 1 and 2 divided by insulated joints 3 and 4. Sources of energy 5 and 6 are bridged across the rails of the track sections in such a manner that they will cause the current to flow through the rails of sections 1 and 2 respectively, thence 60 through wires 7, 8 and 9, 10 to energize their respective magnets 11 and 12 of the selector relay.

Normally the magnets 11 and 12 will be energized and will therefore attract their 65 respective armatures 13 and 14, which carry respectively the contact fingers 19, 44 and 20, 45 mounted on insulating blocks 46, 47, 48, and 49, keeping front contacts 15 and 16 closed and back contacts 17 and 18 open, 70 both contacts 19 and 20 also being open.

Contacts 15, 16, 17 and 18 correspond to the contacts on a neutral relay and it is obvious that these may be duplicated to any necessary extent for the control of circuits 75 extraneous to the selected circuit such as straight track circuit control for automatic railroad signals.

21 is the contact selector and is arranged to select between the closing of contacts 19 80 and 20, being constructed of a flexible support or spring 22 rigidly held at its base by means of a clamp, 23 its upper end being free to move and carry an insulating block 24 formed with selector points, 25 and 26, 85 and carrying contact springs 27 and 28 which are electrically common to supporting spring 22.

The crossing signal 29 is normally held clear by means of energy from battery 30 90 passing through wire 31, wire 32, contact 16, wire 33, contact 15, wire 34, wire 35, through signal 29 back to battery 30.

When a train enters track section 1 in the direction indicated by the arrow energy 95 from battery 5 is shunted thereby deenergizing magnet 11. This will allow armature 13 to fall by gravity opening front contact 15 and breaking the holding circuit to the crossing signal 29 and causing the same to operate, giving indication of the approach of a train. In the meantime, contact 19 has

fallen upon the inner sloping face of selector point 25 as shown at 36 in Fig. 2, and contact selector 21 has therefore, been moved over as shown against the action of its spring 22, but it will be noticed that the action of the selector in no way interferes with the completion of the stroke of the armature 13, the movement of which is solely limited by the back contacts 17.

10. This condition pertains until the front wheels of the train pass the insulated joints 4 and 3, when the magnet 12 becomes deenergized in the same manner as magnet 11. This allows armature 14 to drop, opening front contact 16. On account of the previous movement of contact selector 21, contact 20 will now fall on the outside of selector point 26 and will slide down under contact spring 28 as shown at 37 in Fig. 2.

20. When the train has completely passed into track section 2 magnet 11 will again become energized and pick up its armature 13 closing front contact 15 and lifting contact 19 to its original position. A circuit will now be closed from battery 30, through wire 31, contact 20, contact spring 28, spring 22, wire 38, wire 33, contact 15, wire 34, wire 35, through signal 29, back to battery 30.

This will energize the signal 29 and clear 30 the same. After the train has finally left track section 2, magnet 12 will again be energized, picking up its armature 14, closing front contact 16, lifting contact 20 to its original position and allowing contact selector 21 to assume its central position, all 35 apparatus having now assumed its normal position.

Obviously this sequence of operations will be identical whichever direction the train 40 is traveling. It will be observed that the contact points 19 and 20 in the foregoing are adjusted to be normally just inside the selector points 25 and 26 so that the first contact to drop will fall on the inside of 45 the selector point. The only necessary change in the relay to control a bell is to so adjust the contact points that they are just outside the selector points 25 and 26, as shown in Fig. 4 in order that the first one 50 to drop will fall on the outside of the selector point.

The operation of the relay for the control of a bell is very much the same as for a signal except for a slight variation in the circuits which operate the bell.

In this case it is not essential to use any other contacts than the selected contacts, for the bell control, which therefore leaves all the independent front and back contacts of 60 the two sides of the relay free, for the control of signals or other purposes.

When the train enters track section 1, Fig. 4 relay magnet 11 is deenergized allowing armature 13 to fall. Contact 19 will pass

down the outside of selector point 25 and 65 under contact spring 27, as shown at 39 in Fig. 3 thereby forcing contact selector 21 over.

This will close the bell ringing circuit from battery 40, through bell 41, wire 42, 70 wire 31, contact 19, contact spring 27, spring 22, wire 43 to battery 40.

The train next enters track section 2 and thereby deenergizes relay magnet 12, which drops armature 14 and allows contact 20 75 to pass down the inside face of selector point 26.

When the train has completely left the track section 1 armature 13 will be restored thereby lifting contact 19 and opening the 80 bell ringing circuit.

Thus, it will be seen that with the present relay selector contacts for the control of crossing bells, etc., may be controlled, in conjunction with the normal automatic signal control circuits in such a manner that each set of circuits will operate in its own individual manner and entirely separately distinct from the other set of circuits.

I do not wish to be restricted to the specific constrictions shown and described, as this is only one of many methods of constructing my apparatus without departing from the spirit of my invention.

What I claim as new, and desire to secure by Letters Patent of the United States, is:—

1. A relay comprising two electromagnets, an armature controlled by each electromagnet, a circuit controller governed jointly by 100 said armatures, and other circuit controlling devices governed by said armatures separately.

2. In a relay, in combination: two electromagnets, an armature controlled by each 105 electromagnet, a circuit controller governed by said armatures and capable of being closed by either of said armatures, the operation of said circuit controller to its closed condition by either one of said armatures 110 rendering said circuit controller incapable of being closed by the other armature and other circuit controlling devices governed by said armatures.

3. In a relay, in combination: two electromagnets, an armature controlled by each electromagnet, a contact attached to each armature and insulated therefrom, a movable contact arranged to coact with either of said first mentioned contacts when either 120 of said armatures drops, the dropping of either of said armatures causing said movable contact to move out of the path of the other contact, and other circuit controlling devices governed by said armatures.

4. A relay comprising two electromagnets, an armature controlled by each electromagnet, a contact attached to each armature and

insulated therefrom, a movable contact member arranged to coact with either of said first mentioned contacts, and resilient means for conducting current to said movable contact member and for returning said movable contact member to its normal position.

5. A relay comprising two electromagnets, an armature controlled by each electromagnet, a member of insulating material attached to each armature, a contact secured to the lower face of each member, and a movable contact arranged to coact with either of said first mentioned contacts when either of said armatures drops, the dropping of either of said armatures moving said movable contact out of the path of the contact on the other armature.

6. In a relay, in combination: two electromagnets, an armature controlled by each electromagnet, a contact attached to each armature and insulated therefrom, a movable contact arranged to coact in accordance with the sequence of operation of the armatures with either of said first mentioned contacts when said armatures drop, the dropping of either of said armatures causing

said movable contact to move relative to the path of the other contact, and other circuit controlling devices governed by said armatures.

30

7. A relay comprising two electromagnets, an armature, controlled by each electromagnet, a member of insulating material attached to each armature, a contact secured to the lower face of each member, and a movable contact arranged to coact in accordance with the sequence of the operation of the armatures with either of said first mentioned contacts when said armatures drop, the dropping of either of said armatures moving said movable contact relative to the path of the contact on the other armature and other circuit controlling devices, controlled by said armatures, which are operative irrespective of the sequence of operation of the armatures.
